UNITED STATES PATENT OFFICE.

HUGH COACHMAN ALLSTON, OF ADAMS RUN, SOUTH CAROLINA.

BARREL-MAKING MACHINE.

Application filed October 25, 1923. Serial No. 670,746.

To all whom it may concern:

Be it known that I, HUGH C. ALLSTON, a citizen of the United States, residing at Adams Run, in the county of Charleston and 5 State of South Carolina, have invented a new and useful Barrel-Making Machine, of which the following is a specification.

This invention relates to an improved barrel making machine, which is especially 10 adapted for making barrels of the type which consists of strips of veneer, held by series of hoops inside and outside and studded thereto.

The general object of the invention is to 15 provide a machine for making barrels of this type, and by which the entire process of making the barrel may be carried out continuously and mechanically without removing the barrel from the machine. The 20 process of making the barrel includes the clamping of the inner hoops and the veneer in their proper relative position, expanding the veneer into the shape of the completed barrel, and then feeding all of the outer 25 hoops and simultaneously studding the same as the expanding mechanism with the barrel is rotated step by step.

This invention is in the nature of an improvement over the construction shown in 30 my earlier application No. 593,112, filed October 7, 1922, which was designed to apply the outer end hoops, the barrel being then transferred to another machine for forming the bulge and applying the intermediate outer hoops.

The present invention comprises novel 40 means for supporting the barrel blanks during the initial part of the process, novel means for clamping and holding the veneer, shaping and expanding the same, as well as various other novel details of construction and combinations of elements which will be more fully pointed out in the following detailed description, which is to be read in 45 connection with the accompanying drawings.

In the drawings:

Figure 1 is a front elevation of a barrel 50 making machine constructed in accordance with my invention.

Figure 2 is a vertical section taken longitudinally through the barrel supporting means, with the barrel in position thereon.

Figure 3 is an enlarged sectional view 55 taken longitudinally through the barrel sup-

porting means, showing the same in position to receive the next blank.

Figure 4 is a vertical section taken transversely of the barrel supporting means on the line 4—4 of Figure 2. 60

Figure 5 is a sectional view taken on the line 5—5 of Figure 2, with the veneer and hoops omitted.

Figure 6 is a sectional view taken transversely through the mandrel on the line 65 6—6 of Figure 2, and showing the expanders in elevation.

Figure 7 is an end elevation of the hub and wings on which the expanders are mounted. 70

Figure 8 is a detail sectional view taken on the line 8—8 of Figure 3.

Figure 9 is a detail sectional view taken on the line 9—9 of Figure 4.

Figure 10 is a detail sectional view taken 75 on the line 10—10 of Figure 5.

Figure 11 is a sectional detail view showing one of the expander heads with means for clamping the inner hoop.

Figure 12 is a detail horizontal sectional 80 view through the gearing at the upper left hand corner of the machine, as viewed in Figure 1.

Figure 13 is an end elevation of the same.

Figure 14 is a detail view through the 85 actuating shaft, showing one of the clutch members.

Figure 15 is a plan view of the same.

As shown in Figure 1 of the drawings, the machine includes a horizontal supporting base 1, from which rises a pedestal 2, preferably in the form of a hollow casting and integral with the base 1. At a convenient height, the pedestal is formed with a transverse opening 3, as illustrated in Figure 2, in which a suitable elongated tubular bearing member 4 is secured by means of a set screw 5, or other suitable means. A mandrel 6 is journaled on the member 4, and held against longitudinal movement 90 thereon between a shoulder 7, formed on the pedestal, and a plate 8 secured by screws 9, or other suitable means, to the outer end of the member 4. The mandrel 6 is adapted to be rotated step by step through the medium of a ratchet wheel 10 secured to the inner end thereof in any suitable manner, and actuated by means which will be subsequently described. A spindle 11 is slidably 100 mounted within the member 4, and has a

transverse slot 12, as shown in Figure 14, through which a suitable actuating shaft 13 may be passed.

The pedestal 2 includes a transverse slot 14, through which a suitable actuating shaft 15 may be passed.

The pedestal 2 includes a transverse slot 16, through which a suitable actuating shaft 17 may be passed.

The pedestal 2 includes a transverse slot 18, through which a suitable actuating shaft 19 may be passed.

The pedestal 2 includes a transverse slot 20, through which a suitable actuating shaft 21 may be passed.

spider 12 journaled on its outer end and held between a shoulder 13 and nut 14, secured to the end of the spindle.

A series of hubs 15 are secured by set 5 screws 16 or the like on the mandrel 6 in spaced relation, there being one hub for each hoop of the barrel. Each hub is surrounded by a series of radial wings 17 formed integral therewith or otherwise secured thereto, and forming a substantially 10 continuous circular head, the wings being separated only by narrow slots 18. The outer faces of the wings are formed with laterally extending arcuate flanges 19, and 15 the sides of the wings adjacent the slots 18 are formed with angular flanges 20, which form opposed channels, within which are guided the stems 21 of the arcuate barrel supporting and expanding heads 22. 20 Each head 22 is formed with lateral in-turned flanges 23, forming a channel within which to receive the inner hoop 24, around which the veneer 25, forming the sides of 25 the barrel, is to be secured. Secured underneath the edges of the flanges 23, in each head 22, is a leaf spring 26, which extends into the channel of the next adjacent head, so that the heads 22 and springs 26 together 30 form a continuous circular bearing surface, on which the hoop 24 may rest while the barrel is being stapled. The springs 26, as shown in Figure 10, may be secured by means of screws 27 passing through one of the flanges 23.

35 It will be understood that a series of expanding heads 22 is provided under each hoop, and the outer surface of the head is sloped, as shown in Figure 2, to correspond to the curvature of the completed barrel. 40 The wings 17 adjacent the inner end of the barrel are also provided on the inner side with pairs of opposed flanges 28, as shown in Figures 2 and 6, each pair forming a guideway for the stem 29 of a clamping head 45 30, which has an inwardly projecting arcuate flange 31, adapted to extend over the end of the barrel and clamp the same to the innermost expanding head 22. The outer end of the barrel is held against the outer expanding head 22, by means of a 50 wire hoop 31^a.

55 For the purpose of actuating the clamping head 31 and expanding heads 22, a series of blades 32 are provided, which are pivoted at their outer ends, as at 33, to the revoluble spider 12, and which traverse the respective slots 34 formed in the inner ends of the stems 21 and 29, respectively. The blades are adapted to be moved 60 longitudinally by the reciprocation of the spindle 11, and are slidably connected to the stems 21 and 29 by means of pins 35, which extend across the slots 34 and through cam slots 36 extending longitudinally of the 65 blades and having inclined portions, which

serve to expand and contract the heads 22 and 30 at the proper time and in the proper sequence. Secured to the mandrel 6 between certain of the expanding heads are a number of hubs 37, each provided with pairs 70 of outwardly extending fingers 38, forming slots 39 between them for receiving the respective blades 32. Across each slot 39 is secured a pin or bolt 40, which extends through a longitudinal slot 41 in the blade 75 32 and guides the same in its longitudinal movement, so as to maintain it always in the same line.

In assembling the expander, each blade 32 is connected with the respective stems 21 80 and 29 by means of the screws 35, and the blade is then introduced through the slots 18 into its proper position and adjacent the hubs 15 and 37, after which the bolts 40 85 may be inserted, thus confining the blades and limiting them to a longitudinal movement.

In starting the operation, the inner hoops 24 are first placed in position, after which the veneer 25 is introduced underneath the flanges 31 and clamped, while the outer end of the veneer is held to proper form between the outer heads 22 and the wire hoop 31^a. 90 For the purpose of retaining the inner hoops 24 until the stapling is commenced, one or more heads 22 under each hoop is provided with a laterally extending lug 42, in which is pivotally mounted a clamping finger 43, which is held against the hoop 24 to retain 95 the latter in position by means of an expandable coiled spring 44.

100 The means for actuating the various instrumentalities will now be explained. The pedestal 2 is provided at its upper end with an extension 45, which may be secured by 105 means of a flange coupling 46 or the like, and this extension at its upper end is provided with a bearing 47, in which is journaled an actuating shaft 48. The outer end of the shaft may be journaled in a bearing 49 provided in a supporting member 50, which is rigidly connected to the pedestal extension 45 by a bar 51, and may be otherwise supported from above. The shaft 48 has a collar 52 secured thereto adjacent a 110 drive gear 53, which is journaled on the shaft and may be connected to the collar 52 by a suitable clutch member hereinafter described, which may be actuated at the will of the operator. The gear 53 is normally driven 115 continuously by a pinion 54 secured on a shaft 55, which is journaled at one end in a boss 56 formed on the pedestal extension 45, and is journaled at its other end in a bearing 57 formed on an arm 58 secured to the extension 45. The shaft 55 is driven by a pulley 59, which may be connected to any suitable source of power. The shaft 48, when clutched to the gear 53, serves, by means of an eccentric 60 and pitman 61, to actuate the 120 125 130

ratchet wheel 10 to cause an intermittent rotative movement of the mandrel 6. During this intermittent rotation, the outer hoops 62 are applied to the outside of the barrel, and are secured to the veneer 25 and to the inner hoops 24 by means of any well known stapling mechanisms 63, which are actuated by means of eccentrics 64 secured to the shaft 48.

- 10 On the opposite side of the gear wheel 53, a pinion 65 is journaled on the shaft 48 and is adapted at the will of the operator to be operatively connected to the gear 53, and driven thereby through the actuation of a clutch, similar to the clutch referred to above, which is actuated to connect the gear 53 to the collar 52, and which will be hereinafter specifically described. The pinion 65 is in mesh with a gear 66 mounted on a stub shaft 20 67, which is supported in bearings 68 formed at the upper end of an arm 69, which may be an integral part of the arm 58. A pinion 70, secured to or formed integral with the gear 66, is in mesh with a gear 71 integrally 25 connected with a sleeve 72, which surrounds the shaft 48, and is journaled in bearings 73 formed at the upper end of the arm 58. Secured to the outer end of the sleeve 72 is a crank disk 74, which is driven through the 30 gearing, just described, from the pinion 65, but at a reduced speed. A crank pin 75 on the disk 74 is connected through a pitman 76 to a bell crank 77 pivoted, as at 78, to the pedestal 2. The opposite arm of the bell 35 crank 77 is connected by means of a link 79 to the spindle 11, so that upon rotation of the crank disk 74, the bell crank 77 is rocked and the spindle 11 thereby reciprocated to expand or contract the heads 40 22 which support the barrel.

The clutch mechanism by means of which the gear 53 is connected to or disconnected from the collar 52, as shown in Figures 14 and 15, includes a clutch member 80, which is pivoted as at 81 to an arm 82 extending from the upper portion of the pedestal cap 45. The gear 53 is provided on its side with a recess forming a shoulder 83, which is adapted to be engaged by a pin 84 slidably 45 mounted in the collar 52, and urged toward the recess by an expansile coiled spring 85. When the clutch member 80 is raised, therefore, the pin 84 is free to engage the shoulder 83, and the collar 52 and shaft 45 will be 50 rotated. When the clutch member 80 is lowered, however, its concave pointed end 86 will ride in a groove 87 formed in the collar, and will engage an inclined slot 88 in the pin 84 to retract the latter and disconnect the collar from the driving gear. The clutch member 80 normally rests in the groove 87 and holds the pin 84 retracted. When it is 55 desired to start the rotation of the shaft 48, the clutch member 80 is raised through the medium of a rod 89, which is raised by the

depression of a pedal 90 pivotally mounted on the base 1.

The opposite side of the gear 53 is also provided with a shouldered recess 91, which is connected to or disconnected from the pinion 65 by means of a clutch member 92, pivotally mounted on the arm 93 extending from the upper end of the arm 58. The clutch member 92, and the mechanism connected therewith, is similar in all respects 75 to the clutch mechanism controlling the operation of the collar 52, and is actuated through the medium of a rod 94 pivotally connected to the clutch member 92 and controlled through a pedal 95, which is located 80 adjacent to the pedal 90. It is to be understood that each of the pedals 90 and 95 is normally held up, and after being depressed is raised again by means of a coiled spring 96, or the like.

In order that the rotation of the barrel may cease at the desired moment and not be carried forward by its inertia, a brake drum 97 is secured to the mandrel 6, and is surrounded by a brake band 98 supported by the pedestal 2, and adjustable by means of a thumb nut 99. The shaft 48 and the sleeve 72 are also provided with similar 90 brakes 100 and 101, respectively.

As a temporary support for the barrel blank when it is being initially placed in position on the machine, a saddle 102 may be provided for supporting the outer end. This saddle is carried by a stem 103, which is yieldingly supported within a sleeve 104, and which at the beginning of the rotative movement of the barrel and the stapling operation may be depressed by means of a pedal 105, which may be locked down by 95 means of a clip 106.

In the operation of the machine, the expanders are first in contracted position and the clamping members 30 expanded, as shown in Figure 3, and the pedal 105 is released and the saddle 102 is in its uppermost position. The inside hoops 24 are then placed between the flanges 23 of the expanders and clamped by means of the spring pressed fingers 43. The sheets of veneer are then placed underneath the flanges 31 of the end clamps 30. The veneer is thus bent into approximately cylindrical shape and the wire hoop 31^a is placed around the outer end, while the same is supported on the saddle 102. The pedal 95 is then depressed 110 to raise the clutch member 92, thus connecting the gear 53 to the pinion 65, which drives the crank disk 74 to operate the expanders. The pedal 95 is immediately released, so that as the gear 65 completes one 115 rotation the clutch is disconnected. At this point, the crank disk 74 will have been rotated to the position shown in Figure 1, in which the spindle 11 is moved to the limit of its left hand movement, and the blades 120 125 130

32 will occupy the position shown in Figure 2. During the initial part of the left hand movement of the blades, the end clamps 30 will be drawn inwardly by the inwardly inclined portions of the left hand slots 36, while the expanding members 22 are moved outwardly by the outwardly inclined portions of the remaining slots in the blades. It will be noted also that the inclined portions of the slots actuating the inner expanders are longer than the inclined portions of the other slots, so that the two hoops nearest the center of the barrel will be expanded to a greater degree than the end hoops, thus forming the usual bulge. The barrel is now firmly held by the expanding heads on the inside, and the flanges 31 and wire hoop 31^a on the outside. The pedal 105 is now pressed downwardly and hooked beneath the clip 106, so that the saddle 102 is lowered out of contact with the barrel, leaving the latter free to be rotated with the mandrel.

The operator now depresses the pedal 90, raising the clutch member 80, and thereby connecting the gear 53 to the collar 52 to rotate the shaft 48. This movement through the eccentric 60 and ratchet wheel 10 rotates the mandrel and the barrel step by step, while the hoops 62 are fed underneath the stapling mechanisms 63, which are simultaneously actuated by the eccentrics 64 to perform the stapling operation. When the stapling operation is completed, the barrel is finished and the pedal 95 is again depressed and immediately released, and the crank disk 74 will then be again rotated through a half revolution bringing the crank pin 75 to its lowermost position and moving the spindle 11 and the blades 32 to their right hand position, as shown in Figure 3, and with the heads 22 contracted the completed barrel may be removed.

From the foregoing description, it will be seen that with this invention the entire operation of assembling the inner hoops, the veneer and the outside hoops into position, and stapling all of the hoops simultaneously with the barrel in its completed form may be carried out continuously and expeditiously without removing the barrel from the machine until the operation has been completed.

While I have shown the specific construction of the various mechanisms for accomplishing the several steps of the operation, it is to be understood that these are merely illustrative, and that many modifications may be made in the details of construction, as well as in the relative arrangement of the same without departing from the salient features of the invention as expressed in the claims.

What is claimed is:

65 1. In a barrel making machine, the combination of a mandrel having a plurality of expandable heads, means for clamping an inside hoop to each head, means on one at least of the heads for holding the veneer about said hoops, means for expanding the inside hoop and the veneer while so held into the shape of a barrel, and means for rotating the mandrel with the veneer and inside hoops so held while the outer hoops are being attached.

70 nation of a mandrel having a plurality of expandable heads, means for clamping an inside hoop to each head, means on one at least of the heads for holding the veneer about said hoops, means for expanding the inside hoop and the veneer while so held into the shape of a barrel, and means for rotating the mandrel with the veneer and inside hoops so held while the outer hoops are being attached thereto.

75 2. In a barrel making machine, the combination of a mandrel having a plurality of expandable heads formed with peripheral channels for receiving the inside hoops, means on the inner head for clamping the veneer against the inside end hoop, means for supporting the outside end of the veneer adjacent the inside hoop of the outer end, means for expanding the heads to expand the veneer into the shape of a barrel while it is so held, and means controllable by the operator for rotating the mandrel with the barrel thereon and stapling the outside hoops thereto.

80 3. In a barrel making machine, the combination of a mandrel having a plurality of expandable heads, means for clamping an inside hoop to each head, an expandible clamp overhanging the inner head and adapted to clamp the veneer thereto, means for contracting said clamp to engage the veneer and simultaneously expand each of the heads to press the veneer into the shape of a barrel, and means for rotating the mandrel with the barrel so held while the outer hoops are applied.

85 4. In a barrel making machine, the combination of a pedestal having an elongated bearing member secured thereto and extending laterally, a hollow mandrel mounted for rotation on the bearing member and having a plurality of heads each comprising a plurality of radially movable sections, means for clamping an inside hoop to each head, means on the inner head for clamping the veneer, and means for moving the head sections outwardly to expand the veneer so held into the shape of a barrel, and means for rotating the mandrel with the inside hoops and veneer so held while the outer hoops are being attached.

90 5. In a barrel making machine, the combination of a pedestal having an elongated bearing member secured thereto and extending laterally, a hollow mandrel mounted for rotation on the bearing member and having a plurality of heads, each comprising a plurality of outwardly movable sections and formed with peripheral channels for receiving the inside hoops, means on the inner head overhanging the outwardly movable sections for clamping the veneer, means for moving the head sections simultaneously outwardly to expand the veneer so held with the sections of the inside heads moving a

- greater distance than the sections of the end heads so as to bulge the intermediate part of the barrel, means for rotating the mandrel with the barrel thereon, and means
 5 for stapling the outside hoops thereto during said rotation. 70
6. In a barrel making machine, the combination of a mandrel having a plurality of radial guideways, heads having slotted stems slidably mounted in said guideways, blades extending longitudinally of the mandrel and traversing said slots, said blades having longitudinal cam slots therein, pins secured in said stems and extending through said cam slots, means for clamping inside hoop strips to the respective heads, means for clamping the veneer in proper relation to the hoop strips to form a barrel, and means for simultaneously moving all of said blades longitudinally to expand the heads while the inner hoop strips and veneer are so held. 75
7. In a barrel making machine, the combination of a pedestal having an elongated bearing member secured thereto and extending laterally, a hollow mandrel mounted for rotation on said bearing member, said mandrel having series of wings forming radial guideways between them, a plurality of heads made up of arcuate sections, each section having a slotted stem slidably mounted in one of said guideways, a plurality of blades having cam slots therein, pins secured in said stems and extending through said cam slots, means for clamping inside hoop strips to the respective heads, means overhanging the head at the inner end to clamp the veneer in proper relative position to form a barrel, and means for moving all of said blades longitudinally to expand said heads. 80
8. In a barrel making machine, the combination of a mandrel having a series of spaced heads, each comprising a plurality of radially movable sections, means for clamping an inside hoop strip to each of said heads, an end clamp adjacent the innermost head and comprising a plurality of radially movable sections, each having a flange overhanging the adjacent head section and its hoop clamping means, and means for moving the head sections radially and at the same time moving the end clamp sections radially but in the opposite direction to the head sections. 85
9. In a barrel making machine, the combination of a mandrel having a series of spaced heads, each comprising a plurality of radially movable sections, an end clamp adjacent the innermost head and comprising a plurality of radially movable sections, each having a flange overhanging the adjacent head sections, means for simultaneously moving all of said head sections radially outwardly, with the sections of the inside heads moving a greater distance than the sections of the end heads, and means for moving the end clamp sections at the same time radially inwardly to clamp and hold the veneer. 90
10. In a barrel making machine, the combination of a pedestal having an elongated tubular bearing member secured thereto and extending laterally, a hollow mandrel journaled on said bearing member and having a plurality of radial guideways, a plurality of heads each made up of sections having slotted stems slidably mounted in said guideways, an end clamp made up of sections and also having stems slideable in certain of said guideways, said clamp having flanges overhanging the sections of the heads, a plurality of blades extending longitudinally of the mandrel and traversing the slots in said stems, said blades having cam slots therein with inclined cam surfaces, pins secured in the stems and extending through said cam slots, a spindle slideable longitudinally within said bearing member and having at one end a spider rotatably mounted thereon and connected with said blades, and means for moving said spindle longitudinally to simultaneously move all of said blades longitudinally and thereby move the head sections and end clamp sections radially, the cam surfaces controlling the end clamp sections being inclined oppositely to the cam surfaces of the other cam slots. 95
11. In a barrel making machine, the combination of a pedestal having an elongated bearing member secured thereto and extending laterally, a hollow mandrel mounted for rotation on the bearing member and having a plurality of heads, each comprising a plurality of outwardly movable sections and formed with peripheral channels for receiving the inside hoop strips, means on the inner head for clamping said hoop strips, means overhanging the latter for clamping the veneer, means for moving the head sections simultaneously outwardly to expand the veneer and hoop strips so held with the sections of the inside heads moving a greater distance than the sections of the end heads so as to bulge the intermediate part of the barrel. 100
12. In a barrel making machine, the combination of a mandrel having a plurality of spaced expansible heads, means for clamping an inside hoop strip to each head, an end clamp adjacent the innermost head, means for moving the end clamp to clamp and hold the inner end of the veneer laid upon the heads, means for holding the other end of the veneer to the heads, means for expanding the heads to expand the hoop strips and the veneer into the shape of the barrel while they are so held, the intermediate heads being expanded to a greater degree than the end heads. 105
13. In a barrel making machine, the combination of a pedestal having an elongated bearing member secured thereto and extending laterally, a hollow mandrel journaled on said bearing member and having a plurality of radial guideways, a plurality of heads each made up of sections having slotted stems slidably mounted in said guideways, an end clamp made up of sections and also having stems slideable in certain of said guideways, said clamp having flanges overhanging the sections of the heads, a plurality of blades extending longitudinally of the mandrel and traversing the slots in said stems, said blades having cam slots therein with inclined cam surfaces, pins secured in the stems and extending through said cam slots, a spindle slideable longitudinally within said bearing member and having at one end a spider rotatably mounted thereon and connected with said blades, and means for moving said spindle longitudinally to simultaneously move all of said blades longitudinally and thereby move the head sections and end clamp sections radially, the cam surfaces controlling the end clamp sections being inclined oppositely to the cam surfaces of the other cam slots. 110
14. In a barrel making machine, the combination of a pedestal having an elongated bearing member secured thereto and extending laterally, a hollow mandrel mounted for rotation on the bearing member and having a plurality of heads, each comprising a plurality of outwardly movable sections and formed with peripheral channels for receiving the inside hoop strips, means on the inner head for clamping said hoop strips, means overhanging the latter for clamping the veneer, means for moving the head sections simultaneously outwardly to expand the veneer and hoop strips so held with the sections of the inside heads moving a greater distance than the sections of the end heads so as to bulge the intermediate part of the barrel. 115
15. In a barrel making machine, the combination of a mandrel having a plurality of spaced expansible heads, means for clamping an inside hoop strip to each head, an end clamp adjacent the innermost head, means for moving the end clamp to clamp and hold the inner end of the veneer laid upon the heads, means for holding the other end of the veneer to the heads, means for expanding the heads to expand the hoop strips and the veneer into the shape of the barrel while they are so held, the intermediate heads being expanded to a greater degree than the end heads. 120
16. In a barrel making machine, the combination of a pedestal having an elongated bearing member secured thereto and extending laterally, a hollow mandrel journaled on said bearing member and having a plurality of radial guideways, a plurality of heads each made up of sections having slotted stems slidably mounted in said guideways, an end clamp made up of sections and also having stems slideable in certain of said guideways, said clamp having flanges overhanging the sections of the heads, a plurality of blades extending longitudinally of the mandrel and traversing the slots in said stems, said blades having cam slots therein with inclined cam surfaces, pins secured in the stems and extending through said cam slots, a spindle slideable longitudinally within said bearing member and having at one end a spider rotatably mounted thereon and connected with said blades, and means for moving said spindle longitudinally to simultaneously move all of said blades longitudinally and thereby move the head sections and end clamp sections radially, the cam surfaces controlling the end clamp sections being inclined oppositely to the cam surfaces of the other cam slots. 125
17. In a barrel making machine, the combination of a pedestal having an elongated bearing member secured thereto and extending laterally, a hollow mandrel mounted for rotation on the bearing member and having a plurality of heads, each comprising a plurality of outwardly movable sections and formed with peripheral channels for receiving the inside hoop strips, means on the inner head for clamping said hoop strips, means overhanging the latter for clamping the veneer, means for moving the head sections simultaneously outwardly to expand the veneer and hoop strips so held with the sections of the inside heads moving a greater distance than the sections of the end heads so as to bulge the intermediate part of the barrel. 130

13. In a barrel making machine, the combination of a mandrel having a plurality of spaced expansible heads, means for clamping an inside hoop strip to each head, an end clamp adjacent the innermost head, means for moving the end clamp to clamp and hold the inner end of the veneer laid upon the heads, means for holding the other end of the veneer to the heads, means for supporting the outer end of the veneer, means for expanding the heads to expand the hoop strips and the veneer into the shape of the barrel while they are so held.

14. In a barrel making machine, the combination of a mandrel having a plurality of radial guideways, heads having slotted stems slidably mounted in said guideways, an end clamp made up of sections also having slotted stems slidable in certain of said guideways, said clamp having flanges overhanging the sections of the adjacent head, blades extending longitudinally of the mandrel and traversing said slots, said blades having longitudinal cam slots therein, pins secured in said stems and extending through said cam slots, and means for simultaneously moving all of said blades longitudinally to expand

or contract said heads, the cam surfaces of the slots in the stems of the intermediate heads being longer than the slots in the stems of the end heads, so as to cause the ends of the intermediate heads to be expanded to a greater degree than the end heads, the cam surfaces controlling the end clamp sections being inclined oppositely to the cam surfaces of the other cam slots.

15. In a barrel making machine, the combination of a mandrel having a plurality of expansible heads formed with peripheral channels for receiving the inside hoop strips, means on the heads for clamping said hoop strips, means overhanging the inner end head for clamping the veneer against the inside end hoop strip, means for supporting the outside end of the veneer adjacent the inside hoop strip of the outer end, and means for expanding the heads to expand the hoop strips and the veneer into the shape of a barrel.

In testimony, that I claim the foregoing as my own, I have hereto affixed my signature.

HUGH COACHMAN ALLSTON.
